US0D1030867S

(12) **United States Design Patent** (10) Patent No.: **US D1,030,867 S**
(45) Date of Patent: ** Jun. 11, 2024

(54) **CLIPBOARD**

(71) Applicant: **KING JIM CO., LTD.**, Tokyo (JP)

(72) Inventors: **Tomohiro Fudo**, Tokyo (JP); **Koichi Tanimoto**, Tokyo (JP); **Tomoyuki Kuriyama**, Tokyo (JP)

(73) Assignee: **KING JIM CO., LTD.**, Tokyo (JP)

(**) Term: **15 Years**

(21) Appl. No.: **29/870,730**

(22) Filed: **Feb. 3, 2023**

(30) **Foreign Application Priority Data**

Primary Examiner — Lauren D McVey

(57) **CLAIM**

The ornamental design for a clipboard, as shown and described.

DESCRIPTION

FIG. 1 is a front view of a clipboard showing our new design;

FIG. 2 is a rear view thereof;

FIG. 3 is a right side view thereof;

FIG. 4 is a left side view thereof;

FIG. 5 is a top plan view thereof; and,

FIG. 6 is a bottom plan view thereof.

Broken lines shown in the drawings illustrate portions of the clipboard, and form no part of the claimed design.

1 Claim, 6 Drawing Sheets
